UNITED STATES PATENT OFFICE.

DAVID G. WEEMS, OF BALTIMORE, MARYLAND, ASSIGNOR TO THE ELECTRO-AUTOMATIC TRANSIT COMPANY, OF SAME PLACE.

ELECTRIC-RAILWAY SYSTEM.

SPECIFICATION forming part of Letters Patent No. 425,964, dated April 15, 1890.

Application filed July 27, 1889. Serial No. 318,840. (No model.)

To all whom it may concern:

Be it known that I, DAVID G. WEEMS, a citizen of the United States, residing at Baltimore city, in the State of Maryland, have invented 5 certain new and useful Improvements in Electric-Railway Systems, of which the following is a full and clear description, reference being had to the accompanying drawings, forming part of this specification, in which—

10 Figure 1 represents a side elevation of a section of elevated railway, showing a locomotive and car thereon. Fig. 2 is an enlarged end view of the same. Fig. 3 represents a transverse sectional view of one of the rails 15 and its insulation, and showing a portion of one of the rail-supporting brackets and its tie-rod. Fig. 4 is a detail showing the meeting ends of the divided axle. Fig. 5 illustrates a detail of one of the rail-supporting brackets 20 with the rails thereon, and showing a centrally-disposed conductor for the electric current. Fig. 6 is an end view and section of the insulating-sleeve for the conducting-strip.

25 My invention relates to certain improvements in the construction of electric railways for the transportation of mail and express packages at a rapid speed over a line of elevated railway; and it consists in the several constructions and combinations of devices 30 which I shall hereinafter fully describe and claim.

To enable others skilled in the art to make and use my invention, I will now describe the same and indicate the manner in which I carry 35 it out.

In the said drawings, A indicates any well-known form of elevated frame-work, to the upper end of which I securely bolt or otherwise fasten metallic stringers or brackets B, whose 40 upper ends are grooved or recessed to receive the vertical webs of the rails C, suitable non-conducting material D being also placed within the grooves or recesses, between the web of the rail and the bracket, to insulate 45 said rail and to enable the electric current to pass through it without danger of grounding.

The rails shown in this case are similar to those described and claimed in an application filed of even date herewith, Serial No. 318,841, 50 and the cars and locomotive have semi-elliptical closing-housings E for the journals of

the main wheels, as more fully disclosed in my former patent, No. 406,803, granted July 9, 1889, the said cars and locomotive having also depending from their housings the supplemental wheels F, which are designed to travel beneath the laterally-projecting flange of the rail, in a manner and for a purpose which is fully set forth in another of my patents—viz., No. 406,802, granted July 9, 1889. 55 60

The main wheels of the locomotive or forward car in this case are mounted on axles G, one or all of which are divided transversely, the adjoining meeting ends of the two parts being insulated from each other and bolted together securely, so as to form, practically, a solid axle, the bolts *a* used for this purpose being insulated from the sections of the axle. From this construction it will be seen that the current which drives the motors on the 65 train passes out on one of the rails, and thence passes through one of the main wheels of the locomotive, and thence into the part of the axle on that side or to the journal-box, and thence is conveyed by a conductor H to the 70 motor. The current, after passing through the motor, is returned to the opposite rail through a conductor H', the other portion of the divided axle, and the wheel on that side, and, finally, to the rail and generating-station. The current therefore passes out on 75 one rail and is returned on the other, the rails and axle and other conducting parts being insulated to prevent "leakage" and to insure the full current passing to the motor. 80 85

Instead of the construction previously described, I may use the form shown in Fig. 5, in which case a copper strip or other conductor J is fitted to the tie-bolts K midway between the rails, and is insulated from the rods by 90 the insulating-bushing L. (Shown in Fig. 6.) In this instance the current passes from the generating-plant into the conductor J, and after passing to and through the motor on the locomotive in the usual manner is returned 95 through one or both rails.

Having thus described my invention, what I claim as new, and desire to secure by Letters Patent, is—

1. In electric railways, the combination of 100 a suitable frame-work, the brackets placed transversely thereon and grooved at each end

to receive the vertical webs of the main rails, a carrier or locomotive having a divided axle, bolts securing the parts of the axle together, and insulating material between the meeting 5 ends of the axle and surrounding the bolts, substantially as described.

2. In electric railways, the combination of a frame or support, the brackets B, adapted to be placed transversely thereon, said brackets having their upper portions near the ends grooved to receive the vertical webs of the 10 main rails, and tie-rods connecting the oppo-

site ends of the brackets, substantially as described.

3. In electric railways, the combination of 15 an elevated frame-work, the rail-supporting brackets thereon having grooved or recessed seats for the rails, the tie-rods for the rails, and a conductor on said rods, but insulated therefrom, substantially as described.

DAVID G. WEEMS.
